UNITED STATES PATENT OFFICE

KONRAD JAGSCHITZ, OF MAINZ, GERMANY, ASSIGNOR TO THE FIRM OF MASCHINEN-FABRIK AUGSBURG-NÜRNBERG A. G., OF NUREMBERG, GERMANY.

TANK.

1,120,199.

Specification of Letters Patent.

Patented Dec. 8, 1914.

Application filed November 24, 1909. Serial No. 529,339.

To all whom it may concern:

Be it known that I, KONRAD JAGSCHITZ, a subject of the Austro-Hungarian Emperor, residing at Mainz, in the Empire of Germany, have invented a new and useful Tank, of which the following is a specification.

This invention has reference to improved tanks in which the strain on the inner surface of the tank material is uniform so that even very large tanks may be constructed of sheet metal, for instance, of uniform thickness in all portions of the tank. The shape or form of the tank is mathematically determined so that for storing a given quantity of water for instance, a minimum of sheet metal is required.

There are known tanks, the convex walls of which are secured between two parallel rings, while said walls are stiffened by supports distributed over the periphery and bearing them at the ends. In such a tank the walls are nearly at right angles to the bottom ring, which is objectionable for the reason, that on this place where the maximum strain prevails the forces suddenly change their direction from the wall to the bottom ring, whereby the materials are unfavorably strained.

My invention relates to improvements in such tanks whereby the said objection is removed.

The chief improvement consists in so forming the bellied wall of the tank as to cause it to gradually run into the plain bottom.

A further improvement consists in so disposing uprights as to connect their upper ends directly with the upper edge of the tank and the top ring, and with the wall by means of struts and diagonals, while their lower ends are connected with supports without the wall.

Another improvement, if preferred, consists in so disposing the vertical supports as to attach their upper ends to the wall at the points where the maximum diameter of the tank is, all the uprights within the wall being in this case omitted.

I will now proceed to describe my invention with reference to the accompanying drawing, in which—

Figure 1 is a vertical radial section through a part of an improved tank, and Fig. 2 is a similar section through a part of a modified tank.

Similar letters of reference refer to similar parts in both views.

The tank illustrated at Fig. 1 consists of a plain bottom *c*, a bellied wall *a*, a top ring *b*, and a plurality of supports distributed over the periphery of the wall *a*, the wall *a*, the bottom *c* and the greater part of the top ring *b* being made from plates. As will be seen, the tank is so formed that its wall *a* gradually runs into the plain bottom *c*. The top ring *b* may be of any known construction and serves for holding together the upper edge of the tank. Each support consists of a support proper *k* outside of the wall *a*, and of a frame within comprising an upright *d*, several struts *e*, several diagonals *f*, and an angle piece *g* connected with the wall *a* by rivets or the like. The support *k* is adapted to be placed on some pillar *m* made from brickwork or the like. The upper end of each upright *d* is connected directly with the upper edge of the wall *a* and the top ring *b*. The bottom *c* is adapted to be placed on a suitable base *h* of concrete or the like. The wall of the tank is curved according to a surface of revolution, the generating line of the wall *a* being a thrust-line. For ascertaining this thrust-line according to any known theory the contents of the tank may be divided into a cylinder of the diameter of the bottom *c* as indicated by the dotted line *i* and into a ring. The weight of the cylinder of liquid is essentially taken up by the bottom *c* and the base *h*, while the weight of the liquid in the annular space between the cylinder surface and the wall *a* in combination with the lateral pressure of all the liquid produces an inclined total pressure for every support. The vertical component of this total pressure requires to be taken up by the support *k* and the pillar *m*. The moments produced by the said total pressure with regard to the imaginary fulcrum at the support *k* require the top ring *b* to take up the corresponding horizontal strain.

Fig. 2 shows a modified tank which differs from the preceding one in that each support is placed entirely outside of the wall *a*, it being an upright *l*, the upper end of which is attached to the tank at the point where its maximum diameter is. The distance *o* between the center line of the support *l* and the point *n* where the wall *a* theoretically ceases and the bottom *c* commences, is of

course larger in Fig. 2 than in Fig. 1, as can be seen. In consequence of this the top ring *b* of the modified tank at Fig. 2 will be partly released by the weight of the liquid 5 in contradiction to Fig. 1, and this the more the larger the distance *o* is. At the same time the bottom *c* is subjected to a greater tension than before, so that it can be better utilized.

10 The tank may be varied within reasonable limits without departing from the spirit of my invention.

I claim:

1. A metallic tank comprising a holder for 15 the liquid composed of a plain bottom, a bellied wall of partial globular shape passing gradually into the plain bottom, means for supporting the bellied wall, and posts in vertical line with said supporting means.

20 2. A metallic tank comprising a holder for the liquid composed of a plain bottom and a bellied wall of partial globular shape and merging gradually into said bottom, a top ring on the outer upper edge of said wall, 25 vertical supports within the tank wall, and

supporting pillars, said vertical supports connecting above with the top ring and extending below to said pillars.

3. A metallic tank comprising a holder for the liquid composed of a plain bottom and 30 an annular bellied wall of partial globular shape and merging gradually into said bottom, the wall extending into a vertical top section, supporting means on said vertical top section, vertical supports within the wall 35 for supporting its upper edge and post outside of the tank wall in vertical line with said vertical supports within the wall.

4. In a metallic tank of the type described, 40 a holder for large quantities of liquid composed of a plain bottom and an annular bellied wall of partial globular shape and merging gradually into the bottom and having a vertical top section, and means for supporting said vertical top section and the 45 bellied wall.

KONRAD JAGSCHITZ.
